UNITED STATES PATENT OFFICE

163,804

FOOT DISINFECTING UNIT

Alex Hyde, Santa Barbara, Calif.

Application May 25, 1950, Serial No. 10,146

Term of patent 14 years

(Cl. D83—1)

To all whom it may concern:

Be it known that I, Alex Hyde, a citizen of the United States of America, residing at Santa Barbara, in the State of California, have invented a new, original, and ornamental Design for a Foot Disinfecting Unit, of which the following is a specification, reference being had to the accompanying drawing, forming a part hereof.

Fig. 1 is a perspective view of a foot disinfecting unit, showing my new design.

Fig. 2 is a rear elevation of the same.

Fig. 3 is an end elevation of the same on a reduced scale, both ends being alike.

What I claim is:

The ornamental design for a foot disinfecting unit, substantially as shown and described.

ALEX HYDE.
